HINGE APPLYING MACHINE

Louis Triolo, Brooklyn, N. Y., assignor to Imperial Paper Box Corporation, Brooklyn, N. Y., a corporation of New York

Application June 28, 1938, Serial No. 216,395

15 Claims. (Cl. 93—55)

This invention relates to new and useful improvements in automatic machinery for box manufacture, and relates more specifically to a tape applying machine.

5 The principal object of the invention is the provision of a novel machine for applying gummed strips of paper or other flexible material to a box and its cover to form a hinge member, and the machine is particularly adapted for applying strips of the flexible hinge material to boxes of paper, cardboard, or other materials having cover members of substantially the same height as the box proper. In other words, a box, usually substantially rectangular in shape, is 10 formed having a base portion and side and end walls, and a cover member is also formed having a top portion and also side and end walls.

In order to hingedly mount the cover on such a box it has heretofore been the practice to place 20 the box and cover adjacent to each other with the side walls thereof in meeting engagement, and then manually apply a strip of adhesive tape or hinge material to the upper meeting edges of such side walls of the box and cover, and to 25 manually press the marginal edges of the tape into firm engagement with the inner surfaces of the opposed side walls of the box and cover, respectively.

This method of manual application of the 30 hinge is slow and tedious and the results are uncertain since the operator does not normally exert enough pressure upon the adhesive material, and the result is a hinge connection of uncertain stability.

35 It is one of the objects of the present invention to provide a machine which will perform this entire operation automatically. To this end the invention comprises a machine provided, first, with a pair of substantially horizontal, vertically 40 spaced conveyor belts upon which the components of the box are fed, one conveyor receiving the cover members and the other one the box members. A box and a cover member are thus 45 alternately fed from their respective conveyors onto another horizontal conveyor moving at right angles to the first conveyors. This latter conveyor which, for convenience, is termed the master conveyor, is intermittently movable and is provided with means for holding the adjacent rear side walls of the box and cover in meeting engagement for application of the flexible hinge strip.

The box and cover having been moved into meeting engagement on the master conveyor, 50 they are then caused to travel forward to an

advanced position wherein they are stopped for application of the hinge. This portion of the device includes an arm which is longitudinally movable horizontally at right angles to the master conveyor. The end of the arm has means for grasping the terminal of a web of the flexible gummed hinge material one-quarter inch or more in width, and drawing the tape over the length of the meeting rear side walls of the box and cover. As the arm reaches the end of its forward 5 stroke, it releases the tape, and the instant it begins its return movement a finger descends upon the outer terminal of the tape, holding in engagement with the upper edges of the meeting side walls of the box and cover. At the end of 10 this cycle a knife descends and severs the tape, at which time the conveyor advances the box and cover to the second position wherein a channel member mounted at the lower end of a vertically reciprocating rod descends upon the tape, 15 loosely pressing it into engagement with the opposed inner side walls of the box and cover. As this channel ascends, the box and cover are again advanced into the final operative position where the tape is firmly pressed into engagement 20 with the portion of the box and cover, which mechanism will be described more in detail hereinafter. The hinge is now complete and the completed box is now ejected from the machine 25 by the conveyor.

30 In the drawings:

Fig. 1 is a front elevation of the complete machine;

Fig. 2 is a side elevation thereof;

Fig. 3 is a top plan view;

Fig. 4 is a top plan view of the mechanism for pressing the tape into firm engagement with the box and cover;

Fig. 5 is a side elevation thereof with the mechanism in raised position;

Fig. 6 is a side elevation partially in section of the mechanism in lowered position;

Fig. 7 is a side elevation of the compressing mechanism with the parts in final compressing position;

Fig. 8 is an enlarged detail view of a portion of the mechanism shown in Fig. 2; and

Fig. 9 is a perspective view of a box and cover showing the hinge which is adapted to be applied by the instant machine secured thereto.

The box and the cover which is hingedly secured thereto is illustrated in Fig. 9 and comprises a square or rectangular box portion 10 having a base 11, end walls 12, a front wall 13, and a rear wall 14. The cover member 15 is of substantially 55

the same size and includes a top 16, end walls 17, a front wall 18, and a rear wall 19, the hinge member 20 being adhesively secured to the inner surfaces of the two rear walls. After the hinge 5 has been secured to the members as hereinafter described, an internal collar is positioned and adhesively secured within the box for the purpose of properly aligning the cover when the box is closed, although this step is not performed by 10 the present machine. In Fig. 9 the hinge member 20 is shown finally secured in place in full lines, and the strip of hinge material is shown in broken lines at 21 in the position it occupies after it is severed from its web and before it is pressed into 15 place.

The covers 15 are suitably fed, top down, onto a horizontal conveyor belt 25 and the boxes are fed, bottom up, onto a second conveyor belt 26 positioned immediately therebeneath, each of 20 such belts being illustrated in Fig. 2 as sloping slightly downwardly toward the machine although they may be positioned horizontally if desired. The belts 25 and 26 are mounted upon spaced belt pulleys 28 at the outer end and pulleys 25 29 adjacent to the machine, such pulleys being revolved by suitable means (not shown). The pulleys 28 are pivotally mounted between spaced vertical arms 31. In order to prevent the boxes from falling off the belts, suitable guide rails 30 33 are mounted on opposite sides of the conveyor belts.

The boxes are fed from the conveyor belts 25 and 26 onto a master conveyor moving at right angles thereto, such conveyor comprising a centrally disposed endless chain 37, carried by spaced sprockets 39 and 40, mounted upon shafts 42 and 43, the shafts being journaled between vertical supports 44 and 45, respectively.

At suitably spaced intervals the chain 37 is 40 provided with carriers 46 comprising angle members which are secured to the individual links of the chain, the space between such carriers being slightly in excess of the combined width of the box and cover. As the boxes are fed to the 45 end of the lower conveyor belt 26, they are received, bottom up, upon a plate 48. Each box is then caused to move forward in the direction of the arrow, as shown in Fig. 1, by engagement with a carrier 46 on the chain 37. As the chain continues to move, the box is guided in its circular course around the sprocket 39 by means of a pair of spaced, curved guide plates 50 having spaced channel portions 51, as shown in Fig. 2.

As previously stated, this secondary conveyor 55 is intermittently movable a predetermined distance in order to successively position the box in its several working stations. The following means are provided for driving such conveyor as well as the other operative portions of the machine: An electric motor, or other prime mover 54, having a shaft 55 is positioned between two vertical supports 57, as shown in Fig. 1. A pulley 58 is mounted on the motor shaft 55 and another and larger pulley 60 is mounted on a shaft 61, journaled upon two vertical supports 63, the pulleys being connected by a belt 64.

The opposite end of the shaft 61 is provided 70 with a second and smaller pulley 66, and a larger pulley 68 is freely mounted on a cam shaft 69 and operatively connected by means of a belt 67. The pulley 68 is of such size and weight as to constitute a flywheel, and when the machine is in operation the pulley is, of course, constantly rotating. Rotation of the cam shaft 69 is controlled by a 75 lever 70 mounted on and keyed to a horizontal

shaft 70'. At the opposite end of the shaft 70' a short lever 71 is mounted and is keyed thereto. A pawl 72 mounted at the outer end of the lever 71 and urged downwardly by a spring 73 engages a portion 74 adjacent to the lower end of a vertical clutch lever 75. The upper end of the lever is operatively connected with conventional clutch means (not shown) between the flywheel 68 and the cam shaft 69. The lever 71 is urged downwardly by means of a spring 76 and accordingly, when the foot treadle 77 on the lever 70 is manually depressed by the operator, the lever 71 moves upwardly along the clutch lever, and when the treadle is released, the pawl 72 engages the portion 74 on the clutch lever, and the spring 76, drawing the lever 71 downwardly, also draws the clutch lever 75 downwardly. The upper end of the lever 75 is connected with suitable clutch means for causing the flywheel to become momentarily keyed to the cam shaft 69 and give it 20 one complete revolution. Inasmuch as such clutch mechanisms are conventional and well-known in the art, no specific structure to accomplish this purpose is illustrated herein.

Rotation of the cam shaft 69 causes four separate functions to be performed or, in other words, causes one stepped movement of each of the parts. The first function is to move the boxes. The primary conveyors 25 and 26 are continuously operating and the master conveyor is, as previously described, intermittently operated under the control of the operator. The following means are provided for moving the master conveyor a sufficient distance to position the respective boxes and covers in their several working stations.

A substantially cylindrical cam structure 79 is mounted upon the cam shaft and is keyed thereto, such cam having, inter alia, an irregular, annular slot 80 providing a pair of equally spaced cam faces. These cam faces 80 are engaged by a roller 82 mounted at the upper end of a lever 83 which is centrally pivoted at 84 on a horizontal arm 85 secured to one of the vertical uprights 57. When the cylindrical cam 79 is given one complete revolution, this roller travels between the cam faces 80, thereby causing the upper end of the arm to oscillate to the right and then to the left again, and causing the lower end of the arm to oscillate to the left and then to the right. Pivoted secured to the lower end of the arm 83 is a vertical lever 87 having a rack portion 88 at its opposite end. This rack portion engages the teeth 90 of a wheel 91 mounted freely on the shaft 42. The toothed wheel 91 is adjacent to another wheel 94 keyed to the shaft 42, said wheel 94 being connected with the toothed wheel by means of a plurality of spring-pressed pawls 95 which engage indented portions 96 on the wheel 94. Thus as the lever 87 is moved to the right and then to the left, it imparts to the toothed wheel 91 an oscillatory motion. When this wheel is viewed as in Fig. 1, the first part of the movement is in a counter-clockwise direction, and while so moving the pawls 90 pass over the indented portions 96. When the lever 87, however, begins its reverse movement, the toothed wheel is rotated in a clockwise direction, and the spring-pressed pawls thereby engage the indented portions of the wheel 94, causing it to rotate the shaft 42 upon which the sprocket wheel 39 is mounted, and in the relation shown in Fig. 1, such sprocket 39 is moved through an arc of 120° or one-third of a revolution.

Thus it will be apparent by this movement that 75

the box is fed onto the plate 48 from the conveyor belt 26, and is caused to travel forwardly in the direction of movement of the conveyor chain 37 by means of the carriers 46. Boxes are fed onto the receiving plate 48 from the conveyor belt 26 at such a speed as to present an additional box as rapidly as one is conveyed away by the carrier. Thus a box from the lower conveyor belt 26 by successive movements eventually passes beyond the sprocket wheel 39, and before it reaches a point adjacent to the conveyor belt 25 a box top is fed onto the conveyor chain 37, and the box and the cover with their rear vertical walls in end to end engagement are thus advanced to the hinged tape-applying station.

The curved guide plates 50 which support the box in its arcuate travel about the sprocket are continued in the guide channels 100. It will be assumed that the box and cover have now been advanced to a point opposite the tape-applying mechanism, which is designated generally as 104. This mechanism is operated by means of a bell crank lever comprising a vertical portion 106 and a horizontal portion 107, which lever is pivotally mounted at 108 on a substantially U-shaped support 109 which is secured to a horizontal bracket 110 secured to the upper end of the spaced vertical supports 57 by means of a screw 111. In order to impart alternate rearward and forward movement to the portion 106 of the bell crank lever, the portion 107 is actuated by means of an eccentric cam 113 secured to the cam shaft 69. In order to impart sufficient movement to the bell crank lever 106, the cam 113 does not directly engage the portion 107 of the lever, but rather engages the upper surface of a second lever 115 pivotally mounted at 116 at the opposite end of the U-shaped support 109.

A pin 118 mounted at the outer end of the lever 115 travels in a slot 119 in the outer terminal of the bell crank lever arm 107, and thus as the cam shaft 69 is given one complete revolution, the cam 113 moves the lever 115 downwardly, thereby moving the lower arm 106 of the bell crank lever an approved distance to carry the hinged tape to the box. The lower end of the lever 106 is pivotally secured at 122 to a link 123, which link is pivotally secured at its opposite end at 124 to a horizontally reciprocating arm 125. This arm is mounted within the brackets 126 having slideways to fit such arm, the brackets being mounted on a horizontal support 127 as shown in Fig. 1.

A pawl 130 is also mounted on the pivotal member 124, and as the vertical portion 106 of the bell crank lever is moved rearwardly, the pivoted pawl 130 carried in the arm 125 also moves rearwardly. The arm reaches its maximum rearward position, and the forward portion 131 (Fig. 3) of the pawl 130 engages a block or projection 133 and moves a reciprocating carriage 135 forward.

The carriage comprises an arm 136 suitably mounted for reciprocating movement, and above the arm a second arm 138 is mounted by means of a plurality of short links 139 secured at their lower ends to the arm 136. The projection 133 is also mounted in the arm 138, and as the pawl 130 engages the member 133, the initial forward movement of the pawl causes the arm 138 to move forward, thereby causing a finger 140 keyed to the forward link 139' to move downwardly. A plate 142 mounted at the forward end of the carriage is engaged by this finger as it moves downwardly, and the forward end of the strip of hinge

material (not shown) is positioned between the plate and the finger. Thus a very slight forward movement of the upper arm 138 causes the forward end of the hinge tape to be grasped between the plate and the finger, and as the pawl 130 continues its forward movement the tape is drawn forward over the box and cover, which, as aforesaid, are now positioned relative to the tape. The web of tape is not illustrated in the drawings but is suitably positioned to the rear of the carriage.

It will be noted in Fig. 1 that the forward end of the finger 140 is formed with a slight cut out portion 144, and as the terminal of the tape reaches its maximum forward position over the adjacent rear side walls of the box, a finger 146 mounted on a shaft 147 descends upon the terminal of the tape within the cut out portion 144, thereby temporarily holding the tape in engagement with the box as the carriage retracts. The means for actuating this finger will be described hereinafter.

When the carriage 135 has reached its maximum forward position, the pawl 130 is raised, thereby releasing the carriage and permitting it to be returned by means of a spring 150 secured at its forward end to the forward link 139' and at its rear end to a stationary extension 151 of the support for the reciprocating arm 136 of the carriage. Means for raising the pawl 130, thereby releasing the carriage, are provided in an arm 153 carried by but spaced from the pawl, as shown in Fig. 3. This arm carries a roller 154 at its forward end which engages a horizontal arm 157. The upper surface of this arm is so shaped that at a proper position in the movement of the roller the pawl is received upwardly, thereby releasing the carriage. As the carriage reaches its fully retracted position, the second function is complete with the exception of the fact that the hinge tape has not yet been severed. A knife 160 is mounted on an arm 161 which is pivotally mounted on the frame at 162, the knife being held in place by means of a spring 163. The knife is actuated by means of a rod 164 connected between the arm 161 and the lever 70 having the foot treadle 77.

As was previously described, the cam shaft is caused to make one complete revolution when the foot treadle is released, thereby also performing the other several functions. The knife, however, is actuated as the treadle is depressed by virtue of the direct link connection between the knife and the lever 70.

After the completion of the tape-applying operation, the box and cover are advanced by the master conveyor to the next operating position wherein the tape, which has taken the position shown in broken lines at 21 in Fig. 9, is loosely pressed into engagement with the inner side walls of the box, preparatory to applying the final pressure in the last operation.

These last two operations are actuated by means of a pitman 170 mounted concentrically of the cam shaft 69 and connected with a longitudinally reciprocating ram 171. A substantially U-shaped channel member 173 is mounted at the lower end of a vertical support 174 secured to a projection 175 at one side of the ram 171, and thus as the box has been moved to a position relative to the U-shaped channel member 173, this channel member descends as the ram descends, thereby pressing the tape into loose engagement with the inner side walls of the box. As the U-shaped channel descends, 75

another member 178 secured adjacent thereto descends also and engages a finger 179 keyed to the shaft 147, thereby depressing the finger 146 which temporarily holds the tape in place upon 5 the upper meeting edges of the box.

After the box has thus been engaged by the channel member 173, it is again advanced to its final operative position wherein means are provided for firmly compressing the tape in engagement 10 with the box. The mechanism is mounted between a pair of spaced arms 183 which are pivotally mounted on the frame at 184. Means are provided for raising the arms upwardly as the box is moved into this final operative position. The arms are next caused to descend and the inner surfaces of the adjacent rear walls of 15 the box and cover are thus positioned between but spaced from a pair of jaws, one of which is mounted rigidly between the two arms, and the other of which is mounted on a pivoted member, also positioned on the two arms.

The operation is such that the initial movement of the reciprocating ram causes the two 20 jaws to move lightly into engagement with the opposed marginal edges of the tape and then the jaws are caused to move slightly downwardly, thus moving the marginal edges of the tape downwardly so that the tape is taut over the upper meeting edges of the box and cover before 25 the final squeezing operation. Further movement of the ram then causes the pivoted member to move downwardly, thereby causing the movable jaw to go firmly into engagement with the box, and thus compressing the walls together 30 with the hinge tape therebetween.

The spaced arms 183 are joined adjacent to their outer ends by means of a transverse plate 185 which carries the stationary jaw 186 on the lower surface thereof. The movable jaw 187 is 35 mounted on a plate 188 which is pivotally carried on the transverse member at 189. The arms and the jaws are adapted to be raised to the position shown in Fig. 5 to permit the box and cover to be moved by the master conveyor to the proper 40 position relative to the jaws. The arms are raised by means of a link 191, the upper end of which is pivotally secured at 192 to the lower end of the ram. The lower end of the link 191 is provided with a slot 195 through which a pin 193, secured to the pivoted plate 188, passes. Thus, as the plate 188 is drawn upwards by 45 means of the link 191, the arms 183 follow. After the box has been properly positioned relative to the jaws 186 and 187, further rotation of the cam shaft causes the ram to descend, thereby 50 lowering the entire structure to the position shown in Fig. 6. When in this position the pivoted arms 183 rest upon a pin 197 mounted adjacent to the outer terminal of one of such arms. This pin is longitudinally movable within narrow 55 limits, and a spring 198 urges the pin downwardly so that in this position the arms rest upon the frame against the compression of the spring.

When in the position shown in Fig. 6, the jaws 186 and 187 lightly engage the inner vertical walls of the box and cover having the tape in place therein, and further rotation of the cam shaft causes the lower end of a pin 201, having a compression spring 202 thereon, to engage the outer end of a plate 199 rigidly mounted on the upper surface of the transverse plate 185. The spring 202 is stronger than the spring 198 on the pin 197, and as the pin 201 descends, the arms 50 183 are moved downwardly until another pin 205

rigidly mounted on one of the arms 183 engages the frame and arrests further downward movement. This pin 205 is shown engaging the frame in Fig. 7.

During the movement of the arms 183 from the position shown in Fig. 6 to that shown in Fig. 7, there is nothing to urge the pivoted plate 188 and its movable jaw 187 downwardly other than the combined weight of these members. This pressure is sufficient, however, to cause the 10 jaws to have a fairly firm engagement with the marginal edges of the tape, and as these jaws descend this short distance, they tend to press the edges of the tape downwardly, thereby taking up any looseness in the tape along the upper 15 edges of the box and cover.

The final downward movement of the ram 171 causes a pin 200 to engage an extension 188' of the pivoted plate 188 and move the same 20 downwardly, thereby causing the movable jaw 20 187 to move toward the jaw 186 and exert the final squeeze on the opposed surfaces of the tape. As the ram ascends, the jaws are first separated and then raised, thereby clearing the way for 25 the completed box and cover to be ejected from the machine by the master conveyor.

It was previously stated that after the hinge structure was completed, a collar was placed in the box portion for properly aligning the box and cover when the cover is in closed position. 30 Means are illustrated in the present machine for applying a glue strip to the interior of the box so that after the completion of the hinge structure, this collar or liner, as the case may be, may be manually inserted and the box thus completed. 35 This glue applying means comprises a glue pot 215 mounted on a horizontal support 216. A glue applying member 217 is mounted at the lower end of a vertically reciprocating arm 218, and as the member 217 ascends from the filled 40 glue pot, it deposits a glue strip on the interior of the box which has been fed from the lower primary conveyor 26 onto the master conveyor.

The vertically reciprocating arm 218 is actuated by means of a rocker arm 220 centrally pivoted on the frame at 221 and actuated at its opposite end by means of a reciprocating arm 222. The upper end of this arm is engaged by a portion 226 of a bell crank lever 227 having a roller 228 at its free end, the roller engaging an annular 50 cam face 229 on the cylindrical cam structure 79. Thus, as the cam 79 is given one rotation, the movement is multiplied to a point wherein sufficient movement is imparted to the reciprocating lever 218 to operate the glue applying 55 member 217.

Another cam face 230 is engaged by a roller 224 and carried at the upper end of a bell crank lever 231, such lever actuating another vertically reciprocating lever 233 which actuates a rocker 60 arm 236 centrally pivoted at 234, the opposite end of the arm being operatively connected with a vertically reciprocating lever 235. The upper end of this lever projects up into the pathway of the box and covers as they are moved by the 65 master conveyor and acts as a stop therefor while the hinge tape is being initially applied. The use of this stop is, however, optional and in many instances is not required.

What I claim is:

1. In a machine of the class described, a conveyor for successively positioning a box in a plurality of operative stations, means at one of such stations for applying a strip of substantially flexible material and means at another station for 70 75

firmly pressing the strip of flexible material into engagement with the box, the first-mentioned means comprising a reciprocating member adapted to grasp the end of the tape, move the tape into a proper position relative to the box, and vertically reciprocating knife for severing the tape from the web from which it is fed.

5. In a machine for applying a hinge to a box and cover, the combination of an intermittent, longitudinally movable conveyor for moving said box and cover to a plurality of operative stations, means for feeding the respective boxes and covers to said conveyor, means at one of the stations for applying a strip of flexible hinge material to the adjacent walls of the box and cover, means at another station for moving the marginal edges of the hinge material into engagement with the opposed vertical walls of the box and cover, and means at a third station for pressing the hinge material into firm engagement with the portions of the box and cover, said means comprising a pair of jaws, a retractable support for said jaws and means for moving the jaws together.

25. 3. A machine for applying flexible gummed hinge tape to a box and cover therefor comprising an endless conveyor adapted to intermittently move a box and cover into a plurality of operative stations, conveyors operating at right angles to the endless conveyor for feeding boxes and covers successively to the endless conveyor, means for feeding the tape from a web of the material to the adjacent walls of the box and cover, said means comprising a reciprocating carriage movable at right angles to the endless conveyor and provided with fingers adapted to grasp the terminal of the tape and apply it to the appropriate portions of the box and cover, means for firmly compressing the tape into engagement with the box and cover, and common means for simultaneously actuating both foregoing means.

4. In a machine for applying a hinge member to a box comprising a base and cover, a conveyor for successively positioning said box in a plurality of operative stations, means at one of such stations for feeding the material comprising the hinge member to the meeting portions of the box and cover, means at another station for pressing the material into engagement with the box, and means at a third station for compressing the material into firm engagement with the box, said latter means comprising a pair of retractable arms, a stationary jaw member mounted between said arms, a movable jaw pivotally mounted on the arms relative to the stationary jaws, and means for moving the movable jaw into engagement with the stationary jaw.

5. In a machine for applying a flexible hinge to a box and cover therefor, a conveyor for successively positioning said box in a plurality of operative stations, means for feeding the boxes to the conveyor, means at one of such stations for feeding the hinge to the box, and means at another station for compressing the material into firm engagement with the box, said latter means comprising a pair of movable arms, a stationary jaw member mounted between said arms, a movable jaw pivotally mounted on the arms relative to the stationary jaws, and means for moving the movable jaw into engagement with the stationary jaw.

6. A machine for applying a strip of hinge material to a box and cover therefor, comprising an endless conveyor for successively positioning said box and cover in a plurality of operative sta-

tions, reciprocating means at one of such stations for feeding the flexible material to the box and cover, means at another station for pressing the material into engagement with the box, and means at a third station for compressing the material into firm engagement with the box, said latter means comprising a pair of arms, a pair of jaw members mounted between said arms, and means for moving one of the jaw members into engagement with the other member.

7. A hinge applying machine comprising an endless conveyor for successively positioning a box and cover therefor in a plurality of operative stations, means at one of such stations for feeding the hinge to the box, means at another station for pressing the hinge into engagement with the box, and means at a third station for compressing the material into firm engagement with the box, said latter means comprising a stationary jaw member, a movable jaw member, a support for said jaw member, and means for moving the movable jaw into engagement with the stationary jaw with the box and hinge therebetween.

8. In a machine for applying a strip of substantially flexible material to a box, an endless conveyor for successively positioning said box in a plurality of operative stations, means for feeding the flexible material to the desired portions of the box, means at another station for pressing the material into engagement with the box, and means at a third station for compressing the material into firm engagement with the box, said latter means comprising a pair of retractable arms, a stationary jaw member mounted between said arms, a movable jaw pivotally mounted on the arms relative to the stationary jaws, and means for moving the movable jaw into engagement with the stationary jaw.

9. A machine for applying a strip of hinge material to a box and cover therefor, comprising a conveyor for successively positioning said box and cover in a plurality of operative stations, reciprocating means at one of such stations for feeding the flexible material to the box and cover, said means comprising a reciprocating carriage movable at right angles to the conveyor, a pair of fingers supported by said carriage adapted to grasp the forward end of a strip of the hinge material and move such strip into applying position relative to the box and cover, and means at a third station for compressing the material into firm engagement with the box, said latter means comprising a pair of arms, a pair of jaw members mounted between said arms, and means for moving one of the jaw members into engagement with the other member.

10. In a machine for applying a hinge member to a box comprising a flanged base and cover the combination of means for applying a strip of flexible hinge material from a web of such material, said means comprising a reciprocating carriage adapted to move in a path parallel with and adjacent to the meeting edges of base and cover to which the hinge strip is to be applied, a pair of fingers mounted adjacent to the forward end of said carriage and adapted to receive the forward end of the strip therebetween, means associated with the carriage for moving said fingers into engagement with the strip as the carriage begins its forward movement, means for holding the forward end of the strip when delivered by the fingers into applying position and a knife adapted to sever the strip from the web after the carriage has returned to starting position.

11. In a machine for applying a hinge member to a box, the combination of means for applying a strip of flexible hinge material from a web of such material, said means comprising a reciprocating carriage, a finger rigidly mounted adjacent to the forward end of said carriage and adapted to receive the forward end of the web in the upper surface thereof, a movable finger mounted above said rigid finger adapted to engage said end of the strip and means associated with the carriage for moving said finger into engagement with the web as the carriage begins its forward movement, and a finger adapted to hold such forward end into engagement with the box during retracting movement of the carriage.
12. In a machine for affixing a hinge member to a box comprising a flanged base and cover, the combination of means for applying a strip of flexible hinge material from a web of such material, said means comprising a reciprocating carriage adapted to move in a path parallel with and adjacent to the meeting edges of base and cover to which the hinge strip is to be applied, a plate rigidly mounted adjacent to the forward end of said carriage and adapted to receive the forward end of the strip on the upper surface thereof, a movable finger mounted above said plate adapted to engage said end of the strip and means associated with the carriage for moving said finger into engagement with the strip as the carriage begins its forward movement, a finger adapted to hold such forward end in engagement with the box after the carriage has moved the strip into applying position and a knife adapted to sever the strip from the web after the carriage has returned to starting position.
13. In a machine of the class described having a conveyor adapted to move a flanged box and cover therefor to a plurality of working stations and means for applying a strip of flexible hinge material to adjacent portions of box and cover, the combination of means for pressing said hinge material into firm engagement with opposed inner side walls of box and cover, said means comprising a pair of jaws, means for supporting said jaws including means for moving said jaws into operative position after the box and cover have been conveyed to the pressing station, means for bringing the jaws into engagement with the hinge strip, a yielding support for retaining one of the jaws while in such engagement and means for moving such jaw to exert final pressure on the hinge portions against such yielding support.
14. In a machine of the class described having a conveyor adapted to move a flanged box and cover therefor to a plurality of working stations and means for applying a strip of flexible hinge material to adjacent portions of the box and cover, the combination of means for pressing said hinge material into firm engagement with opposed inner side walls of said box and cover, said means comprising a pair of jaws having opposed vertical faces, means for supporting said jaws including means for raising the jaws to permit box and cover to be conveyed into the pressing station, means for lowering the jaws after box and cover have entered such position, means for bringing the jaws into engagement with the hinge strip, means for then lowering the jaws to draw the strip downwardly into more firm contact with box and cover and means for exerting final pressure on opposed portions of the hinge strip.
15. In a machine of the class described having a conveyor adapted to move a flanged box and cover therefor to a plurality of working stations and means for applying a strip of flexible hinge material to adjacent portions of box and cover, the combination of means for pressing said hinge material into firm engagement with the opposed inner side walls of box and cover, said means comprising a pair of jaws having opposed vertical faces, means for supporting said jaws including means for raising the jaws to permit box and cover to be conveyed into operative position, means for lowering the jaws after box and cover have entered such position, means for moving one jaw relative to the other to engage the hinge strip, means for then lowering the jaws to draw the strip downwardly into more firm contact with box and cover and means for exerting final pressure on opposed portions of the hinge strip including a reciprocating plunger adapted to engage the movable jaw and means for actuating said plunger.

LOUIS TRIOLO.
